UNITED STATES PATENT OFFICE

JOHN WALKER, JR., OF MELROSE PARK, PENNSYLVANIA, ASSIGNEE TO WALKER MANUFACTURING COMPANY, INC., A CORPORATION OF PENNSYLVANIA

LATCH FOR HEDDLE FRAMES

Application filed May 14, 1930. Serial No. 452,180.

The object of the invention is to provide improvements in latches of that type which are especially designed and particularly adapted for use in heddle frames of looms for the purpose of operatively positioning the heddle bars in a definite predetermined relation.

In heddle frames which are generally of considerable length, it is necessary to support the usual heddle bars intermediate of their ends and in relatively fixed relation with respect to the rails of the frames, yet this support must be of such character as to permit the heddles to be readily shifted past the positions of said supports whenever and in such numbers as may be desired.

Consequently, another object of the invention is to provide means for the purpose mentioned in the form of bolts or other members, adapted to be secured to the heddle frame rails, and an angularly movable element carried by each bolt and adapted in one position to retain one or more heddle bars in operative position, while in another angular position said element permits such bars to be withdrawn laterally from the bolt.

A further object is to provide a device of this character, which is a distinct improvement over the known prior art, due among other reasons to the fact that in the present construction the bar-retaining element, after being released from its relatively shallow latch-like engagement with the bolt head, may be shifted with substantially no effort into a different angular position which permits the removal of the heddle bars at will and as leisurely as may be desired with both hands free, since said retaining element is adapted to be yieldingly held in withdrawn or open position as long as may be necessary by the same spring that normally holds it in operative or closed position, after which it may be as readily returned to its said closed position and again locked to said bolt head, 45 to prevent its accidental disengagement

therefrom and movement with respect thereto. Thus, the present invention eliminates the necessity heretofore of manually forcing the bar-retaining element longitudinally into and holding it in open position against positive spring tension while the bar or bars are being withdrawn therefrom, the heddles counted and shifted upon the bars to the desired extent, and the bars finally replaced. In fact, in the present device no amount of longitudinal shifting of the bar-retaining element with respect to the bolt head will permit the withdrawal of the bars, so that a wide angular movement of said element is requisite to the accomplishment of this end.

In addition to the foregoing, the present invention comprises further details of construction and operation which are brought out in the following description, when read in conjunction with the accompanying drawings, in which Fig. 1 is an elevational view of a heddle frame in which are employed bar-supporting latches comprising one embodiment of the invention; Fig. 2 is an enlarged fragmentary portion of such frame, showing the major portion of one of the improved latches in side elevation; Fig. 3 is a similar view, showing the bar-retaining element of the latch in angularly withdrawn position; Fig. 4 is a section on the line 4-4 of Fig. 2; and Fig. 5 is a section similar to Fig. 4, but in the opposite direction and showing the retaining element slightly shifted into the position in which it is no longer prevented by its engagement with the bolt head from angular movement with respect to said head.

Referring to the drawings, a heddle frame is here shown as comprising parallel oppositely positioned top and bottom rails 1 and 2, connected at their ends by any suitable means such as straps 3. Pairs of heddle-supporting bars 4 and 5 extend longitudinally of the frame parallel with and slightly spaced from the neighboring rails 1 and 2,

and operatively support a series of heddles 6, only portions of which series are shown.

Each of the rails 1 and 2 is provided at one or more intermediate points with a normally vertically extending bore 7, through which extends a bolt 8, having a threaded shank, and upon its outer end being preferably provided with a thumb nut 9 or the like, which bears against a washer 10. Surrounding its inner end each bolt is provided with a nut 11, which if desired may be countersunk into the adjacent surface of the supporting rail, as clearly shown in Fig. 3. Beyond this last-named nut the bolt is surrounded by a suitable coil spring 12, which may be either cylindrical, conical, or otherwise as may be desired, and which at its outer end bears against a washer 13 also surrounding the bolt.

In the form of the device illustrated, the inner end portion of each of these bolts when operatively positioned is provided with a transversely enlarged head, such as is shown in Fig. 4, and in the preferred embodiment comprises an elongated flattened portion 14, from which extend in opposite directions pairs of wings 15 and 16, said wing pairs being spaced apart yet connected by means of a transversely narrower or reduced portion

17 of the bolt head. It is to be understood however that these wing pairs, instead of being integral parts of the bolt itself, may be originally separate therefrom and secured thereto by riveting, welding, or otherwise, or one pair of such wings may be integral and the other such pair originally separate but in practice unitarily connected with the remainder of the bolt. The distance between the similarly directed wings of the two pairs is but slightly larger than the normal height of the heddle bars 4 and 5, so that these bars may enter the spaces between adjacent wings, and thereafter while in such operative position, as shown in Fig. 4, be prevented by said wings from vertical movement or vibration, and be also prevented by the narrow portion 17 of the bolt head from approaching each other.

In order to prevent the heddle bars from becoming accidentally loosened or shifted from their operative positions within the spaces provided for them, they are normally restrained against lateral vibration and from lateral movement in opposite directions by fingers 18, which depend from an element 19, which normally lies in close parallel relation with the bolt head 14, and which is provided at one end with an angularly directed extension 20. This extension is normally between the washer 13 and the adjacent end portion of the bolt head, said element and its angular extension being provided with an elongated aperture 21 through which the shank of the bolt extends with sufficient looseness to permit said member to

be moved angularly upon the wings 15 as a fulcrum into either of the extreme positions shown in Figs. 2 and 3, after which such position of said element will be yieldingly maintained by the spring until manually released therefrom.

The fingers 18 of the element 19 in addition to normally extending across the spaces between bolt head wings, are diagonally directed through said spaces in order that their free end portions 18' may when in operative position engage the opposite surface of the wings 16, somewhat similar to the construction of a double door latch. The element 19 is also provided centrally with an elongated tongue 22, which normally extends between a pair of heddle bars when in operative position, as shown in Fig. 4, in this position also extending well beyond the free end portion of the bolt head 14, and being manually engageable for a slight movement as indicated by Fig. 5 into a position in which the ends 18' of the fingers 18 become free from engagement with the wings 16, thus permitting the bar-retaining member to be removed without effort into the angular position shown in Fig. 3, and releasing the heddle bars for withdrawal in opposite directions from the bolt head.

Thereafter, the heddle bars may be returned into their respective recesses and the member 19 again oscillated into its normal operative position in substantial parallelism with the bolt head, following which movement transverse and if necessary a slight diagonally upward pressure upon the tongue 22 causes the finger terminals 18' to snap latch-like past the wings 16, so that the spring can then force the bar-retaining element into the operative position shown in Figs. 2 and 4.

Having thus described my invention, what I claim and desire to protect by Letters Patent of the United States is:—

1. A heddle bar support, comprising a shank, means to secure said shank to a heddle frame, a head carried by said shank and having a recess adapted to receive a heddle bar, and an element angularly movable with respect to said head in the plane of the heddle frame and in one position being operative to retain a bar in said recess, while in another position said element permits such bar to be withdrawn therefrom.

2. A heddle bar support, comprising a head portion having a recess adapted to receive a heddle bar, and an element angularly movable with respect to said head in the plane of the heddle frame and in one position being operative to retain a bar in said recess, while in another position said element permits such bar to be withdrawn therefrom.

3. A heddle bar support, comprising a head portion having spaced wings providing an intermediate recess adapted to receive a heddle

bar, and an element angularly movable with respect to said head in the plane of the heddle frame and having a finger, said finger in one position of said element extending across said recess and being operative to retain a bar therein.

4. A heddle bar support, comprising a head portion having spaced wings providing an intermediate recess adapted to receive a heddle bar, and an angularly movable element having a finger, said finger in one position of said element extending across said recess and being operative to retain a bar therein and said finger in operative position latching 70 engaging one of said wings to prevent accidental release of the bar.

5. A heddle bar support, comprising a head portion having an angularly directed wing, said head and wing forming a support for a bar against movement in two directions, and an element angularly movable with respect thereto in the plane of a supporting heddle frame, said element having a finger, and said element and its finger when in operative position forming an additional support for the bar against movement in two other directions.

6. A heddle bar support, comprising a head portion having a wing, and an element angularly movable with respect thereto in the plane of a supporting heddle frame, said element having a finger, said element and its finger normally cooperating with said head and wing to form a substantial closure adapted to receive a bar, which can be withdrawn from such closure upon the angular movement of said element.

7. A heddle bar support, comprising a head portion having a wing, an element angularly movable with respect thereto in the plane of a supporting heddle frame, said element having a finger, said element and its finger normally cooperating with said head and wing to form a substantial closure adapted to receive a bar, which can be withdrawn from such closure upon the angular movement of said element, and means to yieldingly maintain said element and its finger in operative position.

8. A heddle bar support, comprising a head portion having a wing, an element angularly movable with respect thereto in the plane of a supporting heddle frame, said element having a finger, said element and its finger normally cooperating with said head and wing to form a substantial closure adapted to receive a bar, which can be withdrawn from such closure upon the angular movement of said element, said finger being adapted to latch-engage said wing, and a spring to yieldingly maintain said element and its finger in operative position.

9. A heddle bar support, comprising a head portion having a wing, said head and wing forming a support for a bar against move-

ment in certain directions, and an element angularly movable with respect thereto in the plane of a supporting heddle frame, said element having a finger, and said element and its finger when in operative position comprising a restraining means to prevent a bar moving in certain other directions.

10. A heddle bar support, comprising a head portion having a wing, said head and wing forming a support for a bar against movement in certain directions, and an element angularly movable with respect thereto, said element having a finger which is in normal latch-engagement with said wing, said element and its finger when in operative position comprising a restraining means to prevent the movement of a bar in certain other directions.

11. A heddle bar support, comprising a head portion having a wing, said head and wing forming a support for a bar against movement in certain directions, an element angularly movable with respect thereto, said element having a finger which is in normal latch-engagement with said wing, said element and its finger when in operative position comprising a restraining means to prevent the movement of a bar in certain other directions, and resilient means to yieldingly maintain said element and finger in operative position.

12. A heddle bar support, comprising a head portion having a wing, said head and wing forming a support for a bar against movement in certain directions, an element angularly movable with respect thereto, said element having a finger which is in normal latch-engagement with said wing, said element and its finger when in operative position comprising a restraining means to prevent the movement of a bar in certain other directions, and resilient means to yieldingly maintain said element and finger in any one of a plurality of angular positions including the operative position.

13. A heddle bar support, comprising a shank, means to secure said shank to a heddle frame, a head carried by said shank and having oppositely disposed recesses adapted to receive heddle bars maintained in spaced relation by said head, and an element angularly movable in the plane of the heddle frame and in one position being operative to retain such bars within said recesses, while in another angular position said element permits such bars to be withdrawn laterally therefrom.

14. A heddle bar support, comprising a shank, means to secure said shank to a heddle frame, a head carried by said shank and having oppositely disposed recesses adapted to receive heddle bars maintained in spaced relation by said head, an element angularly movable in the plane of the heddle frame and in one position being operative to retain such bars within said recesses, while in another

angular position said element permits such bars to be withdrawn laterally therefrom, and resilient means to yieldingly maintain said element in any one of a plurality of 5 angular positions including the bar-retaining position.

15. A heddle bar support, comprising a head portion having oppositely disposed recesses adapted to receive heddle bars maintained in spaced relation by said head, and an element angularly movable in the plane of the heddle frame and in one position being operative to retain such bars within said recesses, while in another angular position 10 said element permits the bars to be withdrawn laterally therefrom.

16. A heddle bar support, comprising a head portion having a laterally extending shoulder and a laterally extending wing, and an element angularly movable upon said shoulder towards and away from said head portion, and operative in one position to 20 secure a heddle bar against said head and said wing.

25. 17. A heddle bar support, comprising a head portion having a laterally extending shoulder and a laterally extending wing, an element angularly movable upon said shoulder towards and away from said head portion, and operative in one position to secure a heddle bar against said head and said wing, and resilient means to yieldingly secure said element in operative position.

18. A heddle bar support, comprising a head portion having laterally extending shoulders and a pair of laterally extending wings, and an element angularly movable upon said shoulders as a pivot towards and away from said head portion, said element 35 in one position being operative to maintain heddle bars upon said wings against said head, and in an angularly related position being adapted to permit such bars to be removed laterally therefrom.

45. 19. A heddle bar support, comprising a head portion having laterally extending shoulders and a pair of laterally extending wings, an element angularly movable upon said shoulders as a pivot towards and away 50 from said head portion, said element in one position being operative to maintain heddle bars upon said wings against said head, and in an angularly related position being adapted to permit such bars to be removed laterally therefrom, and resilient means to 55 yieldingly maintain said element in any one of a plurality of positions as desired including the operative retaining position.

20. A heddle bar support, comprising a head portion having laterally extending shoulders and a pair of laterally extending wings, an element angularly movable upon said shoulders as a pivot towards and away 60 from said head portion, said element in one 65 position being operative to maintain heddle

bars upon said wings against said head, and in an angularly related position being adapted to permit such bars to be removed laterally therefrom, said element when in operative position being latch-engaged with 70 said head, and resilient means to yieldingly maintain said element in any one of a plurality of positions as desired including the operative retaining position.

In testimony whereof I have affixed my signature.
